DEVICE FOR LINING CLOSURES

Harry E. Gerlitzki, Lancaster, Pa., assignor to
Armstrong Cork Company, Lancaster, Pa., a
corporation of Pennsylvania

Application December 31, 1938, Serial No. 248,859

3 Claims. (Cl. 113—86)

My invention relates to a device for lining closures and more particularly to a device for positioning liners in screw threaded closures so as to insure proper adhesive securement of the liner to the closure throughout substantially the entire extent of the area of contact therebetween.

It is well known that in the manufacture of molded closures, particularly in the larger sizes, there is considerable warpage of the head portion of the closure resulting in the creation of a slightly concave or domed inner head surface. Even in the smaller sizes this action will cause the inner surface of the head portion to be elevated out of its normal plane from .005" to .010". This necessitates that the liner be properly deformed out of its normally flat shape to assume the same contour as the head portion, to insure a satisfactory securement by the adhesive disposed between the closure and a liner. Another problem arises in closure assembly by reason of the screw thread formations on the inner surface of the skirt of the closure. In order to insure proper sealing, the liners are generally of greater external diameter than the internal diameter of the skirt at the screw threads and this often results in the liners being deformed or held by the screw thread projections against proper engagement with the head of the closure. This problem exists in both molded and metal screw thread closures and the problem of securing a flat disk-like liner to a concave surface arises in molded closures for the reasons advanced above and in metal closures having a domed head surface for purposes of appearance.

Heretofore, in the lining of such closures, it has been common practice to place a drop of adhesive in the central portion of the closure and then press the liner with a flat pressing surface. This operation has been generally unsatisfactory since considerable adhesive must be used in order to fill the gap which exists between the domed inner head surface and the flat surface of the disk to be secured thereto.

According to my invention, I provide a device which is adapted to engage the central portion of the liner, leaving the edge portion free for deformation, and to urge the central portion of the liner into engagement with the head of the closure throughout its extent, the liner engaging surface of the pressing device being contoured to substantially the contour of the inner surface of the closure in its corresponding area. The device is so constructed and arranged that, after the initial pressing of the central portion of the liner into proper position, an auxiliary pressing surface engages the edge portion of the liner urging it into proper engagement with the head of the closure, overcoming any tendency for the liner to be improperly aligned by reason of engagement with the screw thread formations or by reason of deformation of the peripheral por-

tion of the liner effected by the initial deformation of the central portion thereof.

In the drawing forming a part of this application, there is shown a view, somewhat diagrammatic, of the lining device of my invention mounted upon the reciprocating arm of a closure lining machine.

Referring to the drawing, there is provided a support 2 for the closure to be lined. This may take the form of an index wheel for conveying the closure intermittently into various stations such as the glue applying station, the liner punching station and the liner pressing station shown in the drawing. There is shown a molded closure 3 positioned on the support 2 which closure is provided with screw thread formations 4 molded in the skirt 5 thereof. The head or top portion 6 of the closure at its inner surface is slightly concave and a sealing liner 7 of cardboard, cork, or the like, is shown in position in engagement with the entire inner surface of the head 6. It will be noted that the outer diameter of the liner 7 is of greater diameter than the inner diameter of the screw thread formations 4 so that the liner 7 must be slightly deformed at its periphery so as to pass to its final position beyond the thread formations 4. As a result of this deformation, the liner 7 does not properly engage the head portion 6 throughout the extent of its inner surface.

The lining device proper is shown in partially depressed position in the drawing. The device comprises a supporting pin 8 which is secured to a horizontal arm 9 adapted for reciprocation in a vertical direction to bring the lining device into position within the closure 3 to perform the lining operation and to withdraw the same therefrom to permit delivery of a subsequent closure to be lined to the lining station. In order to accommodate caps of varying size having skirts 5 of varying length, the end 10 of the supporting pin 8 is screw threaded and passes through an opening in the arm 9, being adjustably secured thereto by the clamping nuts 11 and 12. The supporting pin 8 is provided with a shoulder 13 and is reduced in diameter therebelow in the area 14, the end of the reduced portion slidably projecting into an opening in a primary pressing member supporting casing 15. A locking pin 16 is secured to the projecting end 14 of the supporting pin 8 and operates within a slot 17 provided in the casing 15 so that the casing 15 and pin 8 are free for limited movement with respect to each other in a vertical direction. A spring 18 encircles the portion 14 of the pin 8 and is disposed between the shoulder 13 of the pin 8 and the top of the casing 15, urging the casing 15 to a normal position with the pin 16 in engagement with the top of the slot 17 as shown in the drawing.

The casing 15 is provided with a central bore

19 which receives a primary pressing member 20 which is free for limited vertical movement therewithin, being restricted against free movement by a pin 21 secured thereto and operating within a slot 22 provided in the body of the casing 15. The primary pressing member 20 is normally urged to a position exterior of the edge of the casing 15 by a spring 23 which is disposed within the bore 19 and is held under compression between the body of the casing 15 at the bottom 24 of the bore 19 and against the inner surface of the primary pressing member 20. It will be noted that the primary pressing member 20 is provided with a convex outer face 25 of substantially the same contour as the inner surface of the head 6 of the closure 3.

The end 26 of the casing 15 is tapered to a relatively narrow flat annular surface which acts as an auxiliary pressing surface, engaging the edge of the disk 7 to properly position the same in engagement with the inner surface of the head of the closure.

In the operation of my device the closure 3 is fed to the lining station with a lining disk 7 positioned therein and with a stratum of adhesive disposed between the liner 7 and the head 6 of the closure. In many instances the liner will be disposed away from the head being engaged with the screw thread formations. Motion of reciprocation is imparted to the arm 9 in a vertical direction, causing the supporting pin 8 and its associated mechanism to move downwardly until the face 25 of the primary pressing member 20 engages the liner 7. As downward motion continues, the liner 7 is deformed from its planar form and is forced into engagement with the head of the closure, being urged into such position by the face 25 of the primary pressing member. As downward movement progresses, the member 20 is caused to move relative to the casing 15, the pin 21 moving in the slot 22 and thus the pressure of spring 23 is transmitted through the primary pressing element 20 to the liner 7 holding the same in firm engagement with the head of the closure during continued downward movement of the arm 9. As this movement continues, the auxiliary pressing surface 26 of the casing 15 is brought into engagement with the edge of the liner 7 thus causing the same to be properly deformed to assume the contour of the inner surface of the head of the closure by movement of the casing 15 downwardly with respect to the member 20.

Force is transmitted to the casing 15 through the spring 18, and after engagement of the auxiliary pressing surface 26 of the casing 15 with the liner 7, continued downward movement of the arm 9 results in slidable movement of the projecting portion 14 of the supporting pin 8 within the bore of the casing 15, pin 16 being moved away from the top of the slot 17 upon such relative movement. This continues until the arm 9 reaches its lowermost position. The supporting pin 8 is adjustably secured to the support 9 so that movement of the projecting portion 14 of the pin 8 is arrested prior to engagement of the pin 16 with the extreme end of the slot 17 so that the force applied to the casing 15 is always yieldingly cushioned by the spring 18. Upon movement of reciprocation of the arm 9 upwardly, the auxiliary pressing surface 26 remains in engagement with the edge of the liner 7 until the pin 16 engages the casing 15 at the top of the slot 17 whereupon continued upward movement causes the casing 15 to move with respect to the pri-

mary pressing member 20 until such time as the pin 21 engages the lower surface of the slot 22 in the casing 15, and thereafter the arm 9, the supporting pin 8 and the associated mechanism moves unitarily, withdrawing the inserting member from the closure so that the same may be moved from the lining station and a new unlined closure presented thereto.

It will be clear from the foregoing description that by my device the liner is first positioned with its central portion in engagement with the head of the closure and this portion is placed under deforming pressure while permitting free and unrestricted deformation of the edge portion to permit proper and complete conformation of the center portion of the liner with the head of the closure. After such engagement, the liner, about its edge adjacent the periphery, is forced into engagement with the head portion, moving the liner out of engagement with the screw threads if it be lodged there. The liner is held under compression at its central portion during such operation and the edge portion is momentarily held in deformed position and engagement with the head surface until the auxiliary pressing surface is withdrawn.

While I have illustrated and described certain preferred embodiments of my invention, it will be understood that the invention is not so limited but may be otherwise embodied within the scope of the following claims.

I claim:

1. In a device for lining a screw threaded closure having a concave inner head surface with a liner disk of a diameter greater than the inner diameter of the closure at the threads, a primary pressing member of a diameter less than the diameter of the liner disk to be positioned, a convex pressing surface on said primary member engageable with the central portion only of a liner disk to be positioned to press the central portion of such liner disk into conformity with the concave inner head surface of the closure and permit free and unrestricted deformation of such liner disk at its edge, a secondary pressing member carrying said primary pressing member and having an annular pressing surface disposed about the pressing surface of said primary member and engageable with the surface of said liner disk along a line disposed adjacent its edge to press such edge into conformity with the closure head, means yieldingly urging said primary member to a position with its pressing surface exterior of the pressing surface of said secondary member, means for simultaneously moving said pressing members into position within a closure to be lined to thereby bring said primary pressing surface into engagement with the liner disk prior to pressing of the edge portion thereof by the pressing surface of the secondary pressing member, and yielding means disposed between said moving means and said secondary pressing member to limit the pressure applied thereby.

2. A device in accordance with claim 1 in which the pressing members are carried by a support adjustably secured to the means for simultaneously moving the same into position.

3. A device in accordance with claim 1 in which the secondary pressing member is hollow and the primary pressing member is slidable axially therein and in which a spring is provided in the secondary pressing member to move the primary pressing member to the position recited in claim 1.
